UNITED STATES PATENT OFFICE

137,985

DESIGN FOR A CONTAINER FOR SOAP DISPENSERS

Howard G. Mullett, Whitefish Bay, Wis., assignor to Bradley Washfountain Co., Milwaukee, Wis.,
a corporation of Wisconsin

Application December 15, 1943, Serial No. 112,009

Term of patent 7 years

(Cl. D52—2)

To all whom it may concern:

Be it known that I, Howard G. Mullett, a citizen of the United States of America and residing at Whitefish Bay, in the county of Milwaukee and State of Wisconsin, have invented a new, original, and ornamental Design for a Container for Soap Dispensers, of which the following is a specification, reference being had to the accompanying drawing, forming a part thereof.

In the drawing,

Fig. 1 is a side elevational view of a container for soap dispensers, showing my new design, and Fig. 2 is a plan view thereof.

I claim:

The ornamental design for a container for soap dispensers, as shown.

HOWARD G. MULLETT.
